UNITED STATES PATENT OFFICE

124,948

DESIGN FOR A GAME BOARD

Leslie V. Ballard, Webb City, Okla.

Application April 19, 1940, Serial No. 91,791

Term of patent 14 years

To all whom it may concern:

Be it known that I, Leslie V. Ballard, a citizen of the United States, residing at Webb City, in the county of Osage and State of Oklahoma, have invented a new, original, and ornamental Design for a Game Board, of which the following is a specification, reference being had to the accompanying drawing, forming part thereof.

I claim:

The ornamental design for a game board, as shown.

LESLIE V. BALLARD.
